UNITED STATES PATENT OFFICE

2,460,342

TOOL POST AND TOOL FOR LATHES

Allen F. Feaster, Boulder, Colo.

Application July 9, 1945, Serial No. 603,762

2 Claims. (Cl. 82—36)

1

This invention relates to a lathe tool holder and more particularly to a tool post of the type illustrated and described in applicant's copending application Serial No. 534,646, which issued April 24, 1945, as Patent No. 2,374,477.

The principal object of the invention is to provide means for holding a tool in a post of this character by means of which the tool can be adjusted for angle to either side and also for height without disturbing the setting of the complete post assembly.

Another object of the invention is to provide a simple and highly efficient tool post which can be quickly and easily placed in a conventional compound lathe tool rest and which will support the cutting tool in any desired position for any type of work and which, in addition, can be used to guide the tool for accurately forming arcuate convexities or concavities of any desired radius in the work.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a perspective view of the complete improved tool holding attachment for lathes;

Figs. 2 and 3 are cross-sections therethrough taken on the lines 2—2 and 3—3, respectively, Fig. 1;

Fig. 4 is a detail section through the tool holding portion of the device, taken on the line 4—4, Fig. 3; and

Fig. 5 is a rear end view of the improved attachment.

This improved tool post is designed for application to a conventional compound tool rest having a dove-tailed post-receiving channel for receiving and holding the standard tool post. The improved attachment is provided with a foot plate 10 which slides into the dove-tailed groove of the rest and is locked therein by means of a vertical set screw 11 which engages the bottom of the channel of the conventional rest and clamps the plate 10 against the upper sides of the dove-tailed groove thereof.

A pedestal member 12 extends upwardly from the foot plate 10 upon which a pivot post 13 is formed. The post 13 is provided with a medial circumferential groove 14.

A horizontal base member 15 is pivotally mounted at its one extremity on the pivot post 13 and may be clamped at any desired radial position therein by means of a clamp screw 16.

which closes a split 17 about the post 13. A set screw 23 extends inwardly from each side edge of the member 15. The extremities of the screws 23 terminate in the groove 14 to hold the member 15 in place on the post 13. The outer extremity of the base member 15 extends upwardly, or has an upwardly extending block attached thereto, to form a clamp and guide member 18.

A horizontal slide bar 19 passes through a hole drilled through the clamp member 18 with its axis parallel to the base member 15 and intersecting the axis of the post 13. The hole in the member 18 which receives the bar 19 is split as shown at 20 and this split may be clamped together by means of a clamp screw 21 to clamp the bar in any desired position therein. The forward extremity of the bar 19 is threaded or otherwise attached in a slide block 22 having a flat bottom which rests on the base member 15.

A short cylindrical tool supporting plug 24 is vertically and rotatably mounted in a cylindrical socket in the forward extremity of the slide block 22. The upper forward portion of the block 22 is cut back to expose the upper forward portion of the cylindrical tool plug 24. The bottom of the forward portion of the block 22 is not cut back and the socket does not extend completely therethrough so that a supporting shelf 29 is provided for supporting the plug 24 and absorbing the downward thrust thereon. A tool channel 25 extends diametrically through the plug 24 at a downward incline, as shown in Fig. 4, to receive any desired metal cutting tool 26. The tool 26 is locked in its channel by means of a clamp screw 27 extending axially downward from the top of the plug 24. The plug 24 may be locked at any desired radial or vertical position in its socket by means of oppositely acting set screws 28.

When used for turning a ball the conventional tool rest is adjusted to place the axis of the pivot post 13 directly below the center of the desired ball. The cylindrical post is adjusted and set in its socket to place the cutting edge of the tool 26 at the proper point to completely surround and cut-off the ball. The tool is fed to the work by the regular cross feed screw of the tool rest and is caused to travel around the ball by swinging the bar 19 from side to side about the pivot post 13.

For turning a concavity the axis of the pivot post 13 is placed below the center point of the desired concavity and the slide block is moved across the pivot post 13 until the tool contacts the work. The tool is fed to the work by the cross-feed of the standard tool rest and is traversed across the concavity by swinging the bar 19 from side to side about the axis of the pivot post 13.

While a specific form of the improvement has

been described and illustrated herein, it is desired to be understood that the same may be varied, within the scope of the appended claims, without departing from the spirit of the invention.

Having thus described the invention, what is claimed and desired secured by Letters Patent is:

1. Means for adjustably supporting a cutting tool in a lathe tool post comprising: a metallic block; a vertical semi-cylindrical socket formed in the forward extremity of said block, said socket opening through said forward extremity and through the top of said block and having a closed bottom; a vertical, completely cylindrical, tool holding plug snugly and rotatably mounted in said socket; a tool receiving channel extending diametrically through said plug; a cutting tool in said channel; a set screw threaded axially downward into said tool holding plug into contact with said tool for locking the latter therein, said tool projecting forwardly from said plug through the open forward extremity of said block; an apron extending forwardly from said block and forming a bottom in said socket for supporting said plug; and oppositely acting set screws extending through the sides of said socket into contact with said plug for locking the latter in any desired rotatable position.

2. Means for adjustably supporting a cutting tool in a lathe tool post comprising: a metallic block; a vertical semi-cylindrical socket formed in the forward extremity of said block, said socket

opening through said forward extremity and through the top of said block and having a closed bottom; a vertical, completely cylindrical, tool holding plug snugly and rotatably mounted in said socket; a tool receiving channel extending diametrically through said plug; a cutting tool in said channel; a set screw threaded axially downward into said tool holding plug into contact with said tool for locking the latter therein, said tool projecting forwardly from said plug through the open forward extremity of said block; an apron extending forwardly from said block, there being a circular indentation in said apron receiving the bottom of said plug for supporting the latter; and horizontally positioned set screws extending into said socket for locking said plug therein.
